US0D1029269S

(12) **United States Design Patent** (10) Patent No.: **US D1,029,269 S**
(45) Date of Patent: ** *May 28, 2024

(54) **IMPLANTABLE CARDIAC MONITOR**

(71) Applicant: **MEDTRONIC, INC.**, Minneapolis, MN (US)

(72) Inventors: **Matthew T. Vanderpool**, Fridley, MN (US); **Michael R. Klardie**, Plymouth, MN (US); **Kris A. Peterson**, Edina, MN (US)

(73) Assignee: **MEDTRONIC, INC.**, Minneapolis, MN (US)

(*) Notice: This patent is subject to a terminal disclaimer.

(**) Term: **15 Years**

(21) Appl. No.: **29/880,674**

(22) Filed: **Jul. 26, 2023**
